UNITED STATES PATENT OFFICE

CHARLES T. DRAPER, OF CLEVELAND HEIGHTS, OHIO, ASSIGNOR TO THE DRAPER MANUFACTURING COMPANY, OF CLEVELAND, OHIO, A CORPORATION OF OHIO

THREADED BUNG OPENING CONSTRUCTION

Application filed June 27, 1932. Serial No. 619,484.

The invention relates to bung opening construction for metallic containers, barrels, drums, vessels, packages and the like utilized for shipping, storing and/or dispensing fluid, liquid, or semi-solid materials; and relates more particularly to a simplified bung opening construction to which a threaded member may be readily connected, and which may be closed by any one of a number of kinds of usual and well known closure members.

Metallic containers are widely used for transporting, storing and dispensing various kinds of lubricating oils, and pumps having threaded tubular members connected to the containers are invariably utilized for drawing off the contents of such containers. Metallic containers are therefore almost universally provided with threaded bung rings so as to provide for the connection of the threaded tubular members of such pumps to the containers. These threaded bung rings are usually cast, forged or specially pressed and machined members, each of which must be seamed in a liquid tight manner to a wall or head of a metallic container, and the openings provided by the threaded bung rings are closed for the purpose of shipment and storage by a threaded closure plug.

The manufacture of such threaded bung rings and closure plugs, and the assembly of the threaded bung rings to container walls involve considerable expense and therefore add appreciably to the cost of manufacturing containers adapted for threaded connection with a dispensing pump.

A primary object of the present invention therefore is to provide a container bung opening construction in a simple and inexpensive manner, to which a threaded tubular pump element may be readily connected.

A further object of the present invention is to provide a container bung opening construction to which a threaded member may be readily connected without utilizing a separate specially cast, forged or machined, threaded bung ring and the like assembled to the container wall.

A further object of the present invention is to provide a bung opening construction which does not use or require a special bung ring for

connection with a threaded member, and which may be closed for shipping and storage purposes by any one of a number of usual types of closures.

Moreover, it is a further object of the present invention to provide a bung opening construction in which the bung opening includes a neck integral with the container wall and an inturned flange in telescopic threaded connection with a threaded member.

And finally, it is an object of the present invention to provide a container bung opening construction, which accomplishes the aforesaid desiderata, and which has an extremely simple design and a very inexpensive manufacturing cost.

These and other objects may be obtained by the elements, parts, combinations and constructions constituting the present invention, preferred embodiments of which are shown in the accompanying drawing and are hereinafter claimed and described in detail, which may be stated in general terms as including in metallic container construction, a wall provided with a preferably integral tubular neck forming a bung opening for the container projecting or extending preferably inwardly of the container from the wall, the neck terminating in an inturned annular flange or lip, the inturned flange being preferably pre-formed with a thread, and a threaded member in threaded connection with the inturned flange, and said member having a part in abutment with the wall and/or neck for seating the threaded member in the neck.

In the drawing

Figure 1 is a vertical section through a container wall formed with a tubular neck terminating in an inturned annular flange or lip providing a container bung opening;

Fig. 2 is a vertical section similar to Fig. 1, showing the lip notched and formed into one turn of a helical thread;

Fig. 3 is a fragmentary section taken on the line 3-3, Fig. 2, showing the notched lip;

Fig. 4 is a plan view of the bung opening shown in Fig. 2;

Fig. 5 is a vertical section through the bung opening shown in Fig. 2, provided with a thin

metal cup and substantially rigid plug closure;

Fig. 6 is a view similar to Fig. 5 showing the bung opening provided with a thin metal locking cup closure;

Fig. 7 is a view similar to Fig. 5 showing the bung opening provided with a usual threaded plug closure;

Fig. 8 is a view similar to Fig. 5 showing the bung opening provided with a common wooden bung;

Fig. 9 is a vertical section through the bung opening shown in Fig. 2, having a threaded tubular member connected thereto; and

15 Fig. 10 is a vertical section through a bung opening such as shown in Fig. 1 in which the lip has been provided with one turn of a helical thread by a thread forming tool or the like.

20 Similar numerals refer to similar parts throughout the various figures in the drawing.

The wall 11 of the container is preferably initially provided, as shown in Fig. 1, with 25 a preferably integral tubular neck 12, which projects preferably inwardly of the container and terminates in an inturned annular flange or lip 13, to form a bung opening for the container; and the container wall is preferably 30 reinforced against distortion at and adjacent to the opening by providing the raised annular shoulders 14 at and adjacent to the opening.

35 The lip 13 is then provided with one circumferentially complete thread formation preferably by notching the same at 15, as shown in Figs. 2, 3, 4, 5 and 9, and shaping the lip 13 to form one turn of a helical thread 13a.

40 A threaded member, such as a pipe or tubular dispensing pump connection 16 (Fig. 9), having a threaded portion 17, may then be readily and quickly seated in the bung opening in threaded connection with the lip 45 13a.

The pipe threads 17 are slightly tapered, as shown in Fig. 9, so that as they are threaded into the bung opening, the upper threaded parts 17a abut against and bite into the inner surface of the tubular neck 12, and the prevention of downward movement of the part 17a causes the lip thread 13a to be pulled upwardly and thus into the thread 17.

50 In this manner tight substantially annular bearing areas are provided, which are spaced from each other and produce a rigid mounting of the tube 16 in the neck 12. Pump connections are frequently formed with a flange which is tightly drawn downwardly against the shoulder 14 by the engagement of the threads 17 with the thread 13a thus also producing a rigid mounting of the flanged pump connection in the opening.

55 Accordingly, the present improved bung opening construction provides a simple but

efficient threaded bung opening for a metallic container, to which a threaded dispensing pump connector or other threaded member or pipe may be readily connected, without utilizing a specially separately manufactured 70 and assembled bung ring.

Moreover, the improved bung opening construction may be readily closed for shipment and/or storage in liquid tight sealing relation and/or theft indicating sealing relation, 75 by and one of a number of usual closure means, which may be seated in the improved bung opening, as shown in Figs. 5 to 8, inclusive.

80 In Fig. 5, the present improved threaded bung opening is shown provided with closure means, such as shown in my Patent No. 1,838,136, dated December 29, 1931, which includes a preferably thin metal cup-shaped member 18, a preferably solid or substantially rigid plug member 19 formed preferably of wood, hard rubber, or other distortion resisting but unbreakable material, referred to herein as a rigid plug, and a liquid sealing gasket 20.

85 The closure means shown in Fig. 6 for the present improved threaded bung opening is of the type described in my Patent No. 1,381,704, dated June 14, 1921, and includes a thin metal friction cup member 21 provided with locking projections 22 projecting beneath the lip 13a, and a liquid sealing gasket 23.

90 Fig. 7 shows the present improved threaded bung opening provided with closure means including a liquid sealing gasket 24 and a standard threaded plug 25, the threads of which engage the thread lip 13a, and the head part 26 of which clamps the gasket 24 against the container wall thereby being in liquid sealing abutment with the container wall.

95 Fig. 8 shows the present improved threaded bung opening provided with closure means which comprises the ordinary well known wooden or hard rubber bung or stopper 27 100 and the like.

105 A slightly modified form of improved threaded bung opening is shown in Fig. 10, in which the one circumferentially complete thread formation 13b on the inner edge of the lip 13 is provided by passing a threading tool and the like into bung opening shown in Fig. 1.

110 The improved construction fully lends itself to all requirements and uses for metallic containers during shipping, storing and dispensing, and provides a simplified and inexpensive bung opening construction to which a threaded member may be readily connected and which may be closed by any one of a number of kinds of usual and well known closure means, without requiring a special threaded bung ring to be assembled to the container wall.

115 The above description and the drawing

referred to therein, are illustrative of structures embodying my invention, and the claims appended hereto are intended to cover such modifications of and slight changes in 5 the structures shown and described, as are apparent to those skilled in the art.

I claim:—

1. In metallic container construction, a wall provided with a tubular neck projecting therefrom forming a bung opening, the neck terminating in an inturned lip, the lip being provided with a slit, the slit lip being shaped to form one turn of a helical thread, and a threaded member seated in the bung 10 opening in threaded connection with the lip.
2. In metallic container construction, a wall provided with a tubular neck projecting therefrom forming a bung opening, the neck terminating in an inturned lip, the lip being provided with a slit, and the slit lip being shaped to form one turn of a helical thread. 20
3. In metallic container construction, a wall provided with a tubular neck projecting therefrom forming a bung opening, the neck 25 terminating in an inturned lip, the lip being provided with a slit, the slit lip being shaped to form one turn of a helical thread, and closure means seated in the bung opening.
4. In metallic container construction, a 30 wall provided with a tubular neck projecting therefrom forming a bung opening, the neck terminating in an inturned lip, the lip consisting of one circumferentially complete thread formation, and a threaded member seated in the bung opening in threaded connection with the lip. 35
5. In metallic container construction, a wall provided with a tubular neck projecting therefrom forming a bung opening, the neck 40 terminating in an inturned lip, the lip consisting of one circumferentially complete thread formation, a threaded member in the bung opening in threaded connection with the lip, and the threaded member having a 45 part in liquid sealing abutment with the container wall.
6. In metallic container construction, a wall provided with a tubular neck projecting therefrom forming a bung opening, the neck 50 terminating in an inturned lip, the lip consisting of one circumferentially complete thread formation, a threaded member in the bung opening in threaded connection with the lip, and the threaded member having a 55 part in abutment with the neck.
7. In metallic container construction, a wall provided with a tubular neck projecting integrally therefrom inwardly of the container forming a bung opening, the neck 60 terminating in an inturned lip, the lip consisting of one circumferentially complete thread formation, and a threaded member seated in the bung opening in threaded connection with the lip. 65
8. In metallic container construction, a

wall provided with a tubular neck projecting therefrom forming a bung opening, the neck terminating in an inturned lip, the inner edge of the lip consisting of one circumferentially complete thread, and a threaded member seated in the bung opening in threaded connection with the lip. 70

In testimony that I claim the above, I have hereunto subscribed my name.
